CLAIM

The ornamental design for a model vehicle, as shown and described.

DESCRIPTION

FIG. 1 is a front, left and bottom perspective view of a model vehicle, showing my new design;

FIG. 2 is a rear, right and top perspective view thereof;

FIG. 3 is a front view thereof;

FIG. 4 is a rear view thereof;

FIG. 5 is a bottom side view thereof;

FIG. 6 is a top side view thereof;

FIG. 7 is a left plan view thereof;

FIG. 8 is a right plan view thereof;

FIG. 9 is an enlarged view of portion of FIG. 1 thereof;

FIG. 10 is an enlarged view of portion of FIG. 1 thereof;

FIG. 11 is an enlarged view of portion of FIG. 2 thereof; and,

FIG. 12 is an enlarged view of portion of FIG. 2 thereof.

The broken lines shown in the drawings illustrate portions of the model vehicle that form no part of the claimed design. The dot-dash broken lines depict the boundaries of the enlargements that form no part of the claimed design.
